UNITED STATES PATENT OFFICE

96,556

DESIGN FOR A MUSICAL INSTRUMENT
CASE

Maurice Lifton, Belle Harbor, Long Island, N. Y., assignor to Aaron Lifton and Benjamin Lifton, copartners constituting the firm of The Lifton
Mfg. Co., New York, N. Y.

Application April 22, 1935, Serial No. 56,506

Term of patent 14 years

To all whom it may concern:

Be it known that I, Maurice Lifton, a citizen of the United States and resident of Belle Harbor, Long Island, in the county of Queens and State of New York, have invented a certain new, original, and ornamental Design for a Musical Instrument Case, of which the following is a specification, reference being had to the accompanying drawing, forming a part thereof.

Fig. 1 is a perspective view of a musical instrument case, embodying my new design, in closed condition; and

Fig. 2 is a perspective view of the case when opened.

I claim:

The ornamental design for a musical instrument case as shown and described.

Signed at the city of New York, in the county of New York, and State of New York, this 16th day of April, A. D. 1935.

MAURICE LIFTON.

CERTIFICATE OF CORRECTION.

Design No. 96,556.

MAURICE LIFTON.

It is hereby certified that the above numbered patent was erroneously issued to "Aaron Lifton and Benjamin Lifton as copartners" constituting the firm of The Lifton Mfg. Co., as assignee of the entire interest in said invention whereas said patent should have been issued to Maurice Lifton, Aaron Lifton and Benjamin Lifton as copartners, constituting the firm of The Lifton Mfg. Co., as shown by the records of assignments in this office; and that the said Letters Patent should be read with this correction therein that the same may conform to the record of the case in the Patent Office.

Signed and sealed this 17th day of September, A. D. 1935.
